UNITED STATES PATENT OFFICE.

LOUIS DE VRIES, OF CHICAGO, ILLINOIS.

INCUBATOR.

Application filed September 13, 1926. Serial No. 135,024.

My invention relates to incubators, and the main object of the invention is to provide an incubator with means to provide a natural circulation of air, without the use of any fan or air forcing device; another object is to construct the incubator with double walls providing spaces through which the hot air ascends, and which form a central egg chamber through which the heated fresh air descends, thus providing a continuous circulation; and a further object is to provide the incubator with pipes so arranged that the fresh air pipe will extend through the exhaust pipe and up through the incubator, so as to have the fresh air automatically pre-heated and discharged into the egg chamber or main central chamber at the proper degree of temperature, and to circulate downward through said chamber and out through the exhaust pipe, without the use of any forcing means.

Other objects and advantages are accomplished with my invention as will become apparent with the following description taken in connection with the accompanying drawing, in which

Fig. 1 is a plan view of my invention, parts being broken away;

Fig. 2 is a vertical sectional view, taken on line 2—2 of Fig. 1; and

Fig. 3 is a sectional detail, taken on line 3—3 of Fig. 2.

In the present application I disclose my improved incubator in its preferred form of construction, and this comprises a central chamber or egg chamber 4, surrounded by double walls which include the main or outer walls 5 and the auxiliary or inner walls 6 connected to the said outer walls and supported thereon by the use of brackets or connecting elements 7. These inner walls do not reach to either the ceiling 8 or floor 9 of the incubator. The purpose of this double wall construction is to form a sufficient space 10 between each two walls for the warm air to rise between said walls and to descend in the central chamber or egg chamber.

The preferred method of applying heat to the air in the space formed between the double walls 5 and 6 consists of hot gas chambers 11 and 12, one located at each end of the incubator, and which are connected by two heat transferring pipes 13 located in the spaces between said inner and outer walls at the two sides of the incubator, near the

bottom of said walls. One or more entrance doors for the central chamber is provided, and the door 14 is located in a side of the incubator above pipe 13, said door being 60 constructed in a manner identical to said double wall, including the spaced inner and outer walls and the connecting elements 7, and when closed forms a portion of said double wall, suitable hinge means being provided and also suitable fastening means 14', as indicated in Fig. 1.

The means for inducing circulation of air comprises a foul air pipe or exhaust pipe 15 which starts in and extends across the central lower part of the chamber 4, having intake openings 16, and then extends through an inner end wall, downward through the floor of the incubator, and then extends below the floor as a portion 15' to the opposite end of the incubator, thence upward through the floor and through the hot air space 10 between the inner and outer walls, and out through the upper part of the end wall, thence over the hot gas escape or outlet port 17 and opens upwards. A fresh air pipe 18 enters the exhaust pipe 15 at one end of its lower portion 15' and runs the length thereof and emerges therefrom inside of the incubator, then extends upwards through space 80 10 and is bent over near to the ceiling, extending below the ceiling in the form of a coil 19, the middle or inner part 19' of said coil having perforations 20, preferably on the upper side of said part 19' to discharge 90 the air against the ceiling of the incubator. The outlet port or escape 17 is controlled thermostatically, preferably by a damper or valve 21 actuated by a lever 22 and a thermostat 23 which is located in the center of 95 the top of the egg chamber. A heat inlet port 24 is provided in the bottom of chamber 11, for receiving heat from a suitable heat producing device or means 25.

The main walls and top and bottom of the 100 incubator are preferably constructed with sheet metal "s" on the inside, and with a sheet of asbestos "a" on the outside, or other suitable heat insulating and fire resisting material; and the inner walls 6 preferably 105 consist of wood, beaver board, or the like.

The ascending column of the exhaust pipe is made longer than the descending part, and extends from the intake portion downward to a cooler position, under the incubator, and is extended for a greater distance 110 up through the heating space, then the dis-

tance or length of the descending portion of said pipe, wherefore the air moves freely down from the inner perforated portion through the shorter vertical part to the bottom portion 15' and then up through the longer upwardly extending part which extends through the hot air space 10, thus positively providing sufficient and proper movement of the foul air out of the chamber. The exhaust outlet is furthermore placed over the hot air outlet 17, thus when the damper or valve 21 opens by excessive heat it additionally heats the outer part of the exhaust pipe and thereby produces more rapid movement of the foul air at said discharge end of said pipe. The fresh air pipe extends first through the outer or lower part 15' of the exhaust pipe, and then extends up nearly the entire length or height of the hot air space 10, thus producing a gradual pre-heating of the fresh air, since this pipe extends in the reverse direction of travel of the foul air in portion 15' of pipe 15, and then extends upward to the hottest position of the chamber near the ceiling thereof, there discharging the heated fresh air towards the ceiling of the incubator. It may be noted that circulation of fresh warm air through pipe 18 will continue into the main egg chamber even after damper 21 is open, due to the extensive length of the vertical part of fresh air pipe.

It is apparent from the above disclosure that with this construction the foul air is positively drawn from the lower end of the egg chamber and is positively moved outward by the exhaust pipe, and it is also apparent that the fresh air will be pre-heated in the intake pipe and said pipe will discharge the heated fresh air near the top of the chamber, which will then move downward through the central chamber and through the eggs therein, to be taken up and discharged by the exhaust pipe, thus causing a constant circulation of fresh warm air through the egg chamber. Furthermore, the fresh air supply pipe is made of sufficient length and heat is applied thereto, at a portion thereof sufficiently low to cause the air therein to enter the egg chamber at a temperature slightly lower than that of said

egg chamber. The warm air in the foul air exhaust pipe is used in part to heat the lower portion of the fresh air supply pipe, and the action of the foul air exhaust pipe is increased by having it extend over and upward from the damper or escape valve 21. 55

What I claim as my invention and desire to secure by Letters Patent is:

1. An incubator comprising a chamber 60 with double walls forming hot air spaces around said chamber, a heating chamber at each end of said incubator, at the outside of the double walls, and heat transferring conduits connecting said heating chambers and 65 extending through said hot air spaces.

2. An incubator comprising a top and bottom and main walls, inner walls spaced from said main walls, and which stop short of said top and bottom and provide a central 70 chamber with hot air spaces around the same, a heating chamber provided outward of one main wall and having a port for receiving heat and an escape port with a thermostatic control therefor, an exhaust pipe 75 conducting foul air from the central chamber and having its outlet portion extending over said escape port, a second heating chamber on a main wall opposite the first heating chamber, and conduits connecting said heating chambers and located in said hot air spaces. 80

3. An incubator comprising main walls with a top and a bottom thereon, inner walls spaced from said main walls and which stop short of said top and bottom and provide a central chamber and hot air spaces therearound, heating chambers outward of the opposite main walls, conduits connecting said heating chambers and located in said 90 hot air spaces, an exhaust pipe leading from the lower part of the central chamber and extending below the bottom, then up through a hot air space out of the incubator, and an intake pipe extending through the 95 part of said exhaust pipe located below said bottom, then up through the incubator and extending below said top, having outlet openings located adjacent said top.

In testimony whereof I have signed my 100 name to this specification.

LOUIS DE VRIES.
